UNITED STATES PATENT OFFICE

2,576,422

AWNING

Herbert P. Spradling, Dallas, Tex.

Application August 3, 1946, Serial No. 688,202

2 Claims. (Cl. 20—57.5)

1

This invention relates to new and useful improvements in awnings.

One object of the invention is to provide an improved awning of simple, durable construction, which has an unusually pleasing appearance and which retains such appearance for an indefinite period of time.

A particular object of the invention is to provide an improved awning of the well-known ventilated type which is of novel construction in that the means for spacing its overlapping slats are non-visible and do not detract from the appearance of said awning.

An important object of the invention is to provide an improved awning which is formed of metal or other durable material which is non-deteriorating and which will retain its shape so as to be substantially permanent.

Another object of the invention is to provide an improved awning, of the character described, wherein the overlapping slats are fastened to each other as well as to transverse supports, thereby producing a rigid unitary assembly which will withstand winds of high velocity as well as other detrimental weather conditions.

A further object of the invention is to provide an awning, of the character described, wherein the slats are so constructed that snow and rain water is collected and directed longitudinally of said slats and thereby prevented from passing or being blown inwardly of said slats.

Still another object of the invention is to provide an improved awning, of the character described, wherein the spacing means may be omitted at one or more points throughout the length of the slats to permit direct engagement of said slats and thereby reduce the passage of air through the awning.

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is a perspective view, partly in section, of an awning constructed in accordance with the invention,

Fig. 2 is an enlarged, cross-sectional view, showing the relation of the slats and the fastening of the sections,

Fig. 3 is a sectional view, taken longitudinally of the slats, and showing the mounting of said slats, and

2

Fig. 4 is a view, similar to Fig. 3, showing the use of additional spacers.

In the drawing, the numeral 10 designates an awning which includes a front or main section 11 and side or end sections 12 which are fastened to opposite margins of the main section. The latter includes a plurality of elongated slats or elements 13 mounted on the upper or outer surfaces of transversely extending supports or channel bars 14, as is clearly shown in Figs. 2 and 3. It is preferable to construct the slats 13 of thin strips of metal or other suitable material which may be readily formed to the desired shape. The slats are spaced a substantial distance apart and are preferably curved or arced longitudinally. A plurality of similar, spaced slats 15 overlie the slats 13 and are disposed so as to have their longitudinal margins in overlapping relation to the longitudinal margins of said slats 13, whereby the outer or upper slats 15 obstruct the spaces between the inner or lower slats 13 and said slats coact to conceal the bars 14. Suitable bolts 16 extend through the overlapping margins of the slats for fastening the same to the bars and to each other, 25 the inner ends of the bolts receiving nuts 17 which are held against rotation by engaging within the channels of said bar.

As is most clearly shown in Fig. 2, each slat has its longitudinal margins bent outwardly, then laterally and finally inwardly substantially at right angles to provide external, coextensive ribs or flanges 18 at said marginal portions. An external, central ridge or rib 19 is formed intermediate the ribs 18 by grooving or crimping the inner or under surface of each slat. This construction not only increases the rigidity of the slats but also provides longitudinal channels or grooves 20 in the outer surfaces of the slats between the ribs to collect and conduct rain and snow water to the lower ends of said slats. Internal grooves or channels 21 are formed at the longitudinal margins of the slats by the ribs 18 for collecting and conducting any water which passes or is blown between said slats. Since the ribs 18 of adjacent slats are in overlapping relation, the same coact 40 to provide deflectors for preventing water from being blown or passing between said slats and through the awning. The lower end of each slat is preferably rounded as shown by the numeral 45 22, whereby the overlapping slats provide a scalloped effect.

It is desirable to space the overlapping marginal portions of adjacent slats 13 and 15 from each other to permit the circulation of air and the passage of light rays through the awning,

However, such spacing should not be sufficient to permit the rays of the sun to shine directly therethrough or permit the direct passage of rain or other moisture. For spacing the slats, suitable spacers or collars 23 are confined upon the bolts 16 between the flange 18 of each inner slat 13 and the channel 21 of the adjacent outer slat 15. As shown in Fig. 3, it is preferable for the spacers 23 to be used in conjunction only with the bolts which fasten the slats to the intermediate bar 14, whereby the end portions of said slats are in direct engagement with each other. However, if desired, one of the spacers may be carried by each bolt 16 so as to dispose the entire length of the slats in spaced relation as shown in Fig. 4. Manifestly, the use of the spacers is optional and the same may be eliminated or used at any desired point.

Each side or end section 12 include transverse supports or channel bars 24, similar to the channel bars 14, and one of the bars is curved to conform to the curvature of the main section 11 (Fig. 2). A plurality of relatively overlapping and spaced slats 25 and 26, substantially identical to the slats 13 and 15, are fastened to the outer surfaces of the bars 24 by similar bolts 27 and nuts 28 so as to extend substantially vertical. The construction and formation of the slats 25 and 26 is preferably the same as that of the slats 13 and 15, having similar rounded lower ends 29 and, if desired, being maintained in spaced relation by similar spacers or collars 30 which are carried by certain of the bolts 27 between said slats. Suitable angular brackets 31 connect the side or end sections to the main or front section. For supporting the awning, an angular bracket or hanger 32 is carried by certain of the uppermost bolts 16 and is fastened thereto by a suitable nut 33 as shown in Figs. 3 and 4.

As has been hereinbefore set forth, the awning is preferably constructed entirely of metal so as to provide a light weight, durable structure. However, it is possible to employ plastics or other suitable material. By fastening the slats to each other as well as to their supporting bars, a rigid unitary assembly is provided and said bars are concealed from external view by the overlapping of said slats and the positioning of the bars beneath the slats. The use of thin metallic strips in constructing the slats permit the forming of the same to provide drain channels and deflecting flanges, the formation of which increases the rigidity of said slats and enhances the appearance of the same. Although the awning may be formed of corrosion-resistant material, the same are adapted to be painted any desired color or color combination. It is pointed out that the curvature of the main or front section 11 is subject to variation and that the same may be used in conjunction with more than a pair of end or side sections 12 in certain installations. Since the spacers 23 are confined

upon the bolts 16 between the ribs 18 of adjacent slats, the channel 21 of the outer slat receives said spacers and substantially conceals the same.

The foregoing description of the invention is explanatory thereof and various changes in the size, shape and materials, as well as in the details of the illustrated construction, may be made within the scope of the appended claims, without departing from the spirit of the invention.

10. What I claim and desire to secure by Letters Patent is:

1. An awning including, a plurality of parallel slats having their longitudinal margins overlapping each other, a plurality of bars extending transversely of the slats and underlying the same, said slats being formed of elongate strips of thin metal, upstanding, inwardly-directed channels coextensive with the longitudinal margins of each slat, an upstanding, longitudinal rib intermediate the marginal channels of each slat, said channels and ribs providing longitudinal drain channels therebetween in the outer surfaces of said slats, fastening means extending through and securing the overlapping marginal channels to each other and to the bars, and spacers on the fastening means between said overlapping channels and snugly engaging in the overlapping channels of the outer slats to space said slats from the inner slats and increase the rigidity of the awning.
2. An awning including, a plurality of parallel slats having overlapping longitudinal margins, upper, lower and intermediate bars extending transversely of and underlying the slats, said slats being formed of elongate strips of thin metal, upstanding, inwardly-directed channels coextensive with the longitudinal margins of each slat, an upstanding rib intermediate the marginal channels of each slat, said channels and ribs providing longitudinal drain channels therebetween in the outer surfaces of said slats, fastening means extending through and connecting the overlapping marginal channels to each other and to the bars, and spacers on the fastening means of the intermediate bar and snugly engaging in the overlapping channels of the outer slats to space the intermediate portions of the overlapping slats from each other and increase the rigidity of the awning.
